UNITED STATES PATENT OFFICE.

ERNEST L. WOOLLEY, OF PROVIDENCE, RHODE ISLAND.

OIL-BURNING APPARATUS.

Application filed December 29, 1919. Serial No. 348,017.

To all whom it may concern:

Be it known that I, ERNEST L. WOOLLEY, a subject of the King of Great Britain, residing at Providence, in the county of Providence, State of Rhode Island, have invented certain new and useful Improvements in Oil-Burning Apparatus, of which the following is a specification.

This invention relates to oil-burning apparatus for steam boilers or other furnaces, and consists in improvements in the construction, arrangement and method of operation of the same.

One object of the improvement is to provide an oil-burning apparatus which may be installed on coal-burning furnaces without alteration in the structure thereof, and without requiring extensive fitting or machine work thereon.

Another object of the improvement is to provide an apparatus which is simple in construction, economical to manufacture, and proof against derangement or getting out of order.

Another object of the improvement is to render the apparatus economical to operate, easy to regulate, and convenient for cleaning or adjustment.

Another object of the improvement is to render the apparatus universally adaptable for practically all types of boilers, and generally more efficient and economical in operation than other types of oil-burning furnaces now in use.

Further objects of the improvements will appear from the following specification, comprising a detailed description of one embodiment of the invention as illustrated by the accompanying drawings, in which like reference characters designate like parts. In the drawings:

Fig. 1 is a sectional elevation of a usual type of steam boiler furnace showing my improved oil-burning apparatus applied to use thereon;

Fig. 2, a front elevation of the apparatus;

Fig. 3, a vertical, sectional view of the casing of the apparatus taken on the line X—X of Fig. 1, and illustrating the manner in which it is fitted to the fire-door opening of the boiler;

Fig. 4, a vertical, sectional view of the air-damper of the apparatus, taken on the line Y—Y of Fig. 1;

Fig. 5, an enlarged plan view of the cou-

pling between the fuel feed-pipe and the burner-tube; and

Fig. 6, a vertical, sectional view of the same.

My improved apparatus is of that type in which the fuel oil is supplied to the burner under pressure and forced through a nozzle which atomizes it into a conical spray without the use of steam or forced draft. For this purpose I preferably employ a burner having a central orifice with small oil-ducts leading tangentially thereto, and a restricted opening through which the spray is discharged at high velocity. Such a form of burner is described in my pending application for Letters Patent, Serial No. 336,796, filed Nov. 10, 1919, but as this element of the apparatus forms no part of the present improvement it is not herein shown or described in detail.

Referring first to Fig. 1 of the drawings, M designates the masonry of the boiler foundation, forming the fire-box or combustion-chamber C and ash-pit A, and S is the boiler erected thereon. At the front of the boiler is the usual plate or casing F provided with the fire-door opening O, and below it the ash-pit door D.

As shown in Figs. 1, 2 and 3, my improved oil-burning apparatus is embodied in a main casing 2 which is constructed with a cylindrical tube 3 adapted for insertion through the fire-door opening O of the boiler furnace. For this purpose the original fire-door is removed from its hinges and the casing 2 is provided with a flanged plate 4 which fits in its place against the front of the casing F. The plate 4 follows the conventional shape of the door which it displaces, being of substantially rectangular outline with an arched top, as shown more particularly in Fig. 2. Around the margin of the plate 4 are suitable holes for the bolts 5 which fasten it to the boiler front F. The fire-door openings of practically all types of boilers are of standard size and shape so that in applying the casing 2 thereto no cutting away or other alteration of the furnace front is necessary, the only machine work required being the drilling and tapping of holes to receive the fastening bolts 5. In some cases, in order to provide a sealed joint between the casing 2 and the boiler front to insure heat insulation, a suitable lining is packed around the tube 3

of the casing between its sides and the walls of the door-opening O. As illustrated in Fig. 3, I have found it convenient to fit a metal ring 6 to the inner end of the tube 3 and to insert suitably shaped filling-blocks or bricks 7 of fire-clay between the sides of the tube and the walls of the opening O. The ring 6 and blocks 7 are held in place by a filling of cement 8 which renders the 10 joint tight and provides a permanent lining or insulation for preventing the dissipation of the heat from the flame of the burner B arranged within the casing.

At its forward end the cylindrical tube 3 15 of the casing 2 is flared outwardly in a funnel-like portion 9 which merges into an enlarged annulus 10 terminating in an inturned flange 11. The annulus 10 is formed with a cylindrical bearing seat 12 adapted to receive 20 a relatively thin circular band or ring 13 on its periphery. The ring 13 is provided with a plurality of rectangular openings or air-ports 14 adapted to register with corresponding openings 15 cut through the 25 bearing or annulus 10, see Fig. 4. On the side of the ring 13 is a handle 16 by means of which it may be slid around the annulus 10 to open or close the air ports 15. The ring 13 thus serves as a shutter or damper to 30 regulate the admittance of air to the interior of the casing 2 to supply the necessary draft to the burner B, in the manner as hereinafter more fully explained.

The damper-ring 13 is held in place on the 35 annulus 10 by the peripheral rim 17 of a plate or closure 18 which closes the outer end of the casing 2, see Fig. 1. The closure 18 is constructed in the form of a concaved disk of conical cross section, arranged with 40 the apex of the cone projecting into the interior of the annulus 10 to adapt its walls to serve as a deflector for the air currents entering through the ports 15. The closure 18 is held in place at the end of the casing 2 by 45 means of bolts 19 screwed into the flange 11 on the annulus 10. At the center of the closure or disk 18 is an opening 20 through which the burner pipe or tube 21 projects in axial relation to the casing-tube 3. At the 50 side of the burner-opening 20 is a larger sight-opening 22 protected by a hinged cover plate 23 which may be swung to one side to allow inspection of the flame from the burner B.

55 Referring particularly to Figs. 1, 2, 5 and 6 the burner-tube 21 is supported in position within the casing 2 by means of an improved clamping-device or coupling which connects it with the oil-supply pipe, while providing 60 for its convenient detachment for the purpose of cleaning or adjusting the burner B carried at its inner end. On the front of the closure 18 above its central opening 20 is a boss 24 to which is attached a bracket 25 65 held in place by bolts 26. Projecting for-

wardly from the foot of the bracket 25 is a pipe-coupling or union 27 into the side of which is tapped a feed-pipe 28 leading up from the main fuel-supply or pressure-pipe 29. The feed-pipe 28 is joined to a union 70 30 on the supply-pipe 29 with a shut-off valve 31 interposed therebetween, and a second hand-valve 32 at the side of the coupling 27 provides a conveniently disposed controlling-means for regulating the feed of the oil 75 to the burner B. In the top of the union 27 is a pipe-plug 32 which may be removed to permit cleaning the oil passages.

Referring particularly to Figs. 1 and 6, the outer end of the burner-tube or pipe 21 80 is screwed into the lower branch of a U-shaped fitting 34, the upper end of which is adapted to be clamped against the outer end of the coupling 27. To provide a tight union at the joint between these parts their 85 opposed faces are formed with complementary annular grooves 35 and tongues 36 which fit together in male-and-female fashion, as shown in Fig. 6. Referring to Fig. 5, the U-bend fitting 34 is clamped against the 90 coupling or union 27 by means of a yoke 37 pivoted on bolts 38 screwed into bosses 39 on the opposite sides of the coupling. At the outer end of the yoke 37 is a hand-screw 40 having a pointed end which seats in a 95 socket 41 in a boss 42 on the U-bend 34. A triangular lug 43 projects from the forward end of the U-bend 34 beneath the end-piece of the yoke 37 to provide a stop to prevent the yoke 37 from dropping down out of 100 place should the screw 40 become loosened by accident. The construction and arrangement of my improved apparatus having now been described in detail the method of applying it to use will next be explained. 105

In installing the apparatus on any standard type of boiler-furnace the coal grate is removed from the fire-box and the fire-door taken off from its hinges. The tube 3 of the casing 2 is then inserted into the fire-door 110 opening O with its flanged plate 4 set against the boiler front F. Suitably spaced holes are then drilled and tapped into the boiler front or casing F and the bolts 5 inserted through the plate 4 and screwed into the 115 casing. The tube 3 fits quite snugly within the door opening O, but to render it tight therewith the ring 6 is placed at its inner end and the fire-bricks 7 packed around its sides and cemented in place as illustrated in 120 Fig. 3.

The coupling 27 is connected with the fuel-supply pipe 28 and provided with the valves 31 and 32 applied to the line in the manner as before described. The burner-tube 21, carrying the burner B at its end, is joined to the U-bend 34 and the latter placed against the coupling 27 and clamped thereto by means of the yoke 37 and screw 40, with the tube projecting axially into the casing 125 130

2 through the opening 20 at its forward end. The burner B is thus held fixedly in place axially of the tube 3 with its tube 21 connected through the coupling 27 with the feed-pipe 28 leading from the supply-pipe 29. The pipe 29 leads from the source of fuel supply and is usually connected with a heater by means of which the oil is heated to the required temperature to render it more 10 highly combustible. A pump or compressor, not herein shown, is also provided in the pipe line 29 whereby the fuel is fed under pressure in the usual manner as well known in the art.

When the valves 31 and 32 are opened the heated oil will be forced through the pipe 28 and fed to the burner B by way of the coupling 27 and tube 21. As the oil is ejected through the contracted opening in the 20 burner B it is atomized and forced out in a conical spray, which when ignited, gives a flame of great intensity spreading out around the end of the tube 3 into the combustion-chamber C, as indicated in Fig. 1.

25 The feed of the fuel is regulated at the hand-valve 32 and the pressure may be controlled to provide the proper degree of heat in accordance with requirements. The combustion of the fuel is maintained under a 30 suction draft admitted through the air-ports 15, and for this purpose the ports 15 are opened to the required extent by turning the damper-ring 13 on its annulus 10.

It is here particularly called to attention 35 that as the air is drawn through the ports 15 under the suction of the spray forced through the burner B, augmented by the draft from the flue at the rear of the combustion-chamber or fire-box C, the air currents will pass 40 through the partly opened ports at a tangent whereby a whirling action is set up within the combustion chamber. That is to say, the air is caused to swirl around the burner tube 21, as indicated by the arrows 45 in Fig. 1, and as the currents impinge on the conical surface of the deflector-cone 18 this whirling action is augmented and the air given a spiral forward motion to direct it toward the burner tip with greater force 50 thereby tending to heighten the effect of the draft on the flame whereby to cause a more complete combustion of the fuel sprayed from the burner. It has been demonstrated that this peculiar draft action effects a much 55 more complete vaporization of the fuel, causing its particles to be more highly charged with oxygen, and hence increasing the combustion and minimizing the waste. The flame from the burner is thus caused to 60 generate a maximum degree of heat and the apparatus is therefore rendered more highly efficient, with a corresponding economy in fuel.

It is also to be observed that the 35 proved apparatus is adapted for practically

universal application to various types of furnaces without material alteration in the structure thereof and without extensive fitting or machine work thereon. No brick-ing-up or other masonry work is required 70 within the furnace and no cutting away or refitting of the boiler frame is necessary. Moreover, my improved apparatus is particularly simple in construction; economical to manufacture; easy to operate; and much 75 more efficient in use than other types of devices previously employed in the art.

Various modifications might be made in the structure and arrangement of the apparatus which would fall within the spirit 80 and scope of the present invention, therefore, without limiting myself to the exact embodiment herein shown and described, what I claim is:

1. In an oil-burning apparatus, the combination with a tubular casing adapted to be inserted into the fire-door opening of a furnace and provided with a funnel-shaped extension flaring outwardly a considerable distance beyond the front of the furnace with 85 its maximum diameter at the outer end and having air-ports spaced around the circumference of the casing at its enlarged end, of a damper-ring rotatable on the enlarged annulus of the casing to adapt it to open and close the air-ports, a fuel feed-pipe projecting axially into the casing, an oil-burner on the feed-pipe positioned within the smaller diameter of the casing at a distance inwardly 90 beyond the air-ports, and means for connecting the feed-pipe with the source of fuel supply.

2. In an oil-burning apparatus, the combination with a tubular funnel-shaped casing having its smaller end adapted to fit within the fire-door opening of a furnace and provided with a flange for bolting it to the frame thereof, said casing having its larger end flaring outwardly a considerable distance beyond the front of the furnace and terminating in an enlarged annulus provided with air-ports spaced around its circumference, of a damper-ring rotatably mounted on the enlarged annulus and also provided with air-ports, a closure for the outer end of 105 the casing, a fuel-pipe projecting through the closure axially into the casing, an oil-burner at the inner end of said pipe positioned within the smaller diameter of the casing at a distance inwardly beyond the 110 air-ports, and means for connecting said pipe with the source of fuel supply.

3. In an oil-burning apparatus, the combination with a funnel-shaped tubular casing having its smaller end adapted to fit into the fire-door opening of a furnace, said casing having its larger funnel end flaring outwardly beyond the front of the furnace and terminating in an enlarged annulus provided with air-ports, of a damper-ring rotatably 125

- mounted on the enlarged annulus and provided with cooperating air-ports, a closure at the outer end of the casing formed with a conical wall projecting into the interior of 5 the enlarged end of the casing with its apex at the axis thereof to provide a deflector for the currents of air admitted through the ports, an oil pipe projecting through the center of the end-closure and axially into 10 the casing beyond the air-ports, and an oil-burner at the end of said pipe positioned within the smaller diameter of the casing.
4. In an oil-burning apparatus, the combination with a tubular funnel-shaped casing adapted to have its smaller end fitted into the fire-door opening of a furnace with its enlarged funnel end flaring outwardly beyond the front of the furnace and formed with air-ports arranged circumferentially of 15 20 its enlarged annulus, of a damper for opening and closing the air-ports, a closure at the outer end of the casing formed with a conical wall projecting into the enlarged funnel end of the casing with its apex at the axis thereof, a fuel-pipe extending through the apex of the conical wall axially into the casing beyond the air-ports, and an oil-burner at the end of the pipe positioned within the smaller diameter of the casing.
5. In an oil-burning apparatus, the combination with a tubular funnel-shaped casing having its smaller end adapted to fit within the fire-door opening of a furnace and its enlarged funnel end flaring outwardly to a considerable distance beyond the front of the furnace with air-ports arranged circumferentially of its enlarged annulus, of a conical concaved closure fitted to the enlarged funnel end of the casing, a 25 30 35 burner-tube projecting through the closure axially into the casing, a burner at the end of the tube positioned within the smaller di-
- ameter of the casing, a fuel feed-pipe, and coupling means for detachably connecting the burner-tube with the feed-pipe while 45 providing for its removal therefrom for cleaning or adjustment.
6. In an oil-burning apparatus, the combination with a tubular casing adapted for insertion into the fire-door of a furnace and 50 provided with a funnel-shaped extension projecting outwardly beyond the front of the furnace, of a closure at the outer funnel-shaped end of said casing, a bracket mounted on said closure and carrying a pipe-coupling a burner-pipe projecting through the closure into the casing, a U-bend fitting to the end of the burner-pipe, and a yoke-shaped clamp for clamping the U-bend against the coupling to support the burner-pipe in place while connecting it with the 55 coupling.
7. In an oil-burning apparatus, the combination with a tubular casing adapted for insertion into the fire-door opening of a furnace and provided with a funnel-shaped extension projecting forwardly therefrom, of a concaved closure at the forward end of the casing, a pipe-coupling mounted thereon, a fuel feed-pipe leading into the coupling, a 60 65 70 75 burner-tube projecting through the closure into the casing, an oil-burner at the inner end of the tube, a U-bend at the outer end of the tube adapted to fit against the coupling, a yoke pivoted on the coupling to adapt it to swing down over the U-bend, and a hand-screw on the yoke adapted to be screwed against the U-bend to clamp the burner-tube in place while adapting it for 80 convenient detachment for cleaning or adjustment.

In testimony whereof I affix my signature.

ERNEST L. WOOLLEY.
